DRY SPINNING SYSTEM

James J. Burke, Wilmington, Del., assignor to
American Viscose Corporation, Wilmington,
Del., a corporation of Delaware

Application March 1, 1945, Serial No. 580,360

6 Claims. (Cl. 18—8)

1

This invention relates to dry spinning methods and apparatus and is particularly concerned with an improved evaporative medium and system for controlling it.

In accordance with the invention, artificial filaments are continuously spun longitudinally through an evaporative chamber and upon discharge from the medium in the chamber, they proceed into a substantially enclosed space substantially directly to a collecting device therein on which they are wound, with or without twist, in package form, while the solvent-laden atmosphere is continuously withdrawn from the space in which collection is performed, is heated and is then passed through the chamber counter-current to the direction of passage of the filaments therethrough to exert an evaporative effect on the filaments and thereafter is directed to a solvent recovery system.

The system of the present invention provides an evaporative medium that has a favorable influence upon the luster, toughness, and uniformity of the filaments being spun while making use of and recovering the solvent vapors that emanate from the collected package that would otherwise contaminate the atmosphere of the spinning room.

Heretofore, it has been the practice to collect the filaments in the open atmosphere of the spinning room with consequent contamination of this atmosphere with solvent vapors emanating from the packages. To remedy this situation by entirely removing the solvent from the filaments before they emerge from the spinning chambers either by increasing the length of the spinning chamber or by providing devices within the chamber to increase the distance travelled by the filaments within a chamber of conventional size is generally impractical from the standpoint of space required in the first instance and installation and maintenance expense in the latter instance.

By the improved system and arrangement of the present invention, initial cost of installation and the negligible maintenance cost are fully compensated for by the benefits derived from increased recovery of solvent, improvement in quality of the product, and improved working conditions of the operators.

The enclosed space in which the collection is performed is preferably provided with openable sash doors to permit servicing of the take-up system and the frames about the doors may be sufficiently loose, or adjustable openings may be

2

provided, to allow air from the spinning room to be drawn into the space to sweep over the yarn packages and thereby assist evaporation of the solvent therefrom. The solvent-laden air from the enclosure is then directed to a system for feeding a heated evaporative atmosphere to a plurality of the spinning cells or chambers comprising a dust filter, a heater, and a supply manifold for feeding the spinning cells. The solvent-laden air may constitute substantially all of the evaporative atmosphere or any predetermined part of such atmosphere, in the latter case being combined with additional air from the spinning room.

15 The invention will be more particularly described in relation to the accompanying drawings in which:

Figure 1 shows a preferred embodiment in elevational cross-section taken on line I—I of Figure 2;

Figure 2 is a back elevation, with parts in section and parts broken away, of the embodiment of Figure 1;

Figure 3 is a sectional elevation corresponding to Figure 1, but of a modification; and

Figure 4 is a front elevation of a detail of the embodiment of Figure 3.

With reference to Figures 1 and 2, the invention is illustrated as applied to a row of spinning cells or chambers 2. A spinneret 3 in an upper region of each cell issues the filaments downwardly and they proceed about a roller guide 4 and through an opening 5 at the base of the cell completely about a draw roll 6, through a stationary guide 7 to a collecting device 8, which is shown as a cap twister, though any form of take-up device may be used. A lubricant may be applied to the filaments either within the cell or after it emerges from the cell by means not shown. The collecting devices are enclosed by a plurality of doors 9 which may have transparent panes 10 (see Figure 4) to facilitate observation. As shown in Figures 1 and 2, the door 9 is hinged at 11 and a counterweight 12 is connected by a strand 13 to an outer portion of the upper panel of each door, passing over a pulley 14 secured to framework associated with the spinning cells. Handles 15 are provided for opening the doors. When opened, the sash occupies the dotted line position shown in Figure 1.

A distributing manifold 16 extends the length of the row of cells 2 and has a central channel 17 communicating with each of the spinning cells by feed pipes 18. Excess evaporative medium passes through the return passages 19 above and

below the central channel 17 of the manifold and enters a recirculating duct or conduit 20 which communicates with a chamber 21 and a rotatable damper 22 serves to control the flow through the duct 20. The chamber 21 is adapted to receive a predetermined proportion of air from the spinning room atmosphere through conduit 23 provided with a rotatable damper 24. A filter 25 is interposed between the chamber 21 and the suction conduit 26 connected with a fan or blower 27 which discharges into the conduit 28 communicating with the channel 17 of the manifold. Heating means such as a coil 29 may be provided to raise the temperature of the evaporative medium, such as to about 100° C., passing through a conduit 28 and being supplied to the channel 17.

Conduits 30 are provided at spaced intervals along the length of the manifold and connect the return channel 19 with the enclosed space about the take-up means 8. Each cell 2 is provided with a branch connection 31 near its top to discharge evaporative medium into a common duct 32 leading to a solvent recovery system represented by 33.

Figures 3 and 4 show a modification in which instead of hinging the doors, doors 9a are arranged to slide within stationary guide ways 9' which are sloped with respect to the vertical. In addition, a base panel 34 is provided with a plurality of spaced openings 35 which may be closed to a predetermined extent by slideable plates 36 operating within the guide ways 37 above and below the opening 35. Otherwise the system and arrangement of Figures 3 and 4 correspond to those of Figures 1 and 2. In operation, the plates 36, in the case of Figures 3 and 4, are adjusted to provide a predetermined opening at the various points along the bottom panel 34 whereas in Figures 1 and 2 reliance is placed upon the spaces between adjacent doors to allow entrance of air from the surrounding room. If desired, adjustable openings may also be provided in the embodiments of Figures 1 and 2 adjacent or in the bottom portion of the front panels of doors 9. The dampers 22 and 24 are adjusted to provide any predetermined proportion between the medium recycled through conduit 20 and the fresh air introduced at 23. This proportion, as above, may be controlled by closing damper 24 so that substantially all of the evaporative medium is derived from the enclosed space about the take-up or closing means. Alternatively, the medium may be drawn equally from the atmosphere of the spinning room directly through conduit 23 and from the enclosed space about the take-up means through conduit 20. By adjusting either dampers 22 or 24 to intermediate positions, any desired proportion between the solvent-laden atmosphere between the collecting means and fresh air may be obtained in the evaporative medium.

The medium drawn through the filter 25 by the blower 27 is heated to desired temperature by the coil 29 and flows through channel 17 from which it is distributed to the bases of the individual spinning cells through the connections 18 and passes upwardly in each cell, countercurrent to the filaments to a point above the spinneret where it is discharged to the recovery system 33 by branches 31 and header 32. By introducing the solvent-laden air from the take-up enclosure into the return channel 19 of the manifold, it is subjected to filtering and to heating to assure that the evaporative medium used enters the

spinning cells under controlled conditions free of suspended foreign matter, such as dust, and irregularities of temperature distribution which would harmfully effect spinning and decrease the efficiency of the recovery system. By controlling the air flow through the take-up enclosure, such as by the adjustable openings 35 and by controlling the dampers 22 and 24, the spinning conditions within the spinning cells can be varied widely to the extent that the proportion of evaporating medium recycled through channels 19 and duct 20 with respect to the amount sent through passages 18 to the spinning cells depends upon such controls.

It is to be understood that the description hereinabove is illustrative only and that changes and variations may be made without departing from the spirit and scope of the invention as defined by the appended claims.

29 I claim:

1. A method of dry spinning artificial filaments comprising the steps of extruding a solution of the spinning material in a volatile solvent longitudinally through a substantially enclosed evaporative zone, then passing the filaments containing residual solvent into a substantially separately enclosed space and collecting them therein in wound package form, concurrently drawing solvent-laden air from the enclosed space, mixing it with a predetermined proportion of ambient air from the spinning room, heating the mixture to a predetermined temperature, passing a portion of the heated mixture through substantially the entire length of the evaporative zone countercurrently to the filaments, and continuously recycling a portion of the heated mixture to be mixed with a solvent-laden air prior to the heating of the latter.

2. A method of dry spinning artificial filaments comprising the steps of extruding a solution of the spinning material in a volatile solvent longitudinally through a substantially enclosed evaporative zone, then passing the filaments containing residual solvent into a substantially separately enclosed space and collecting them therein in wound package form, concurrently drawing solvent-laden air from the enclosed space, mixing it with a predetermined proportion of ambient air from the spinning room, heating the mixture to a predetermined temperature, passing a portion of the heated mixture through substantially the entire length of the evaporative zone countercurrently to the filaments, and continuously recycling a portion of the heated mixture to be mixed with the solvent-laden air prior to the heating of the latter and then passing the mixture discharged from the evaporative zone to a solvent recovery system.

3. Apparatus for dry spinning artificial filaments comprising a plurality of vertical spinning cells in a row, a spinneret in the upper region of each spinning cell, a manifold back of the spinning cells comprising a main feeding channel and a return channel, conduits connecting the main feeding channel to the spinning cells adjacent their bottoms, take-up means for collecting the filaments in the form of a wound package along the front and outside of the spinning cells, means outside the spinning cell for feeding filaments from the cells to the take-up means, means for substantially enclosing the take-up and feeding means, spaced conduits connecting the feeding and take-up means enclosure with the return channel of the manifold, blowing means having its suction side connected with the return chan-

nel and its discharge side connected with the main channel of the manifold, and heating means arranged between the blowing means and the main channel.

4. Apparatus for dry spinning artificial filaments comprising a plurality of vertical spinning cells in a row, a spinneret in the upper region of each spinning cell, a manifold back of the spinning cells comprising a main feeding channel and a return channel, conduits connecting the main feeding channel to the spinning cells adjacent their bottoms, take-up means for collecting the filaments in the form of a wound package arranged in front and outside of the spinning cells, means outside the spinning cell for feeding filaments from the cells to the take-up means, means for substantially enclosing the take-up and feeding means, spaced conduits connecting the feeding and take-up means enclosure with the return channel of the manifold, blowing means having its suction side connected with the return channel and its discharge side connected with the main channel of the manifold, heating means arranged between the blowing means and the main channel, means for conducting air from the spinning room to the suction side of the blowing means, and means for controlling the proportions of fluid from the return channel and from the spinning room to be received by the blowing means.

5. Apparatus for dry spinning artificial filaments comprising a plurality of vertical spinning cells in a row, a spinneret in the upper region of each spinning cell, a manifold back of the spinning cells comprising a main feeding channel and a return channel, conduits connecting the main feeding channel to the spinning cells adjacent their bottoms, take-up means for collecting the filaments in the form of a wound package arranged in front and outside of the spinning cells, means outside the spinning cell for feeding filaments from the cells to the take-up means, means for substantially enclosing the take-up and feeding means, spaced conduits connecting the feeding and take-up means enclosure with the return channel of the manifold, blowing means having its suction side connected with the return channel and its discharge side connected with the main channel of the manifold, heating means arranged between the blowing means and the main channel, means for conducting air from the spinning room to the suction side of the blowing means, means for controlling the proportions of fluid from the return channel and from the spinning room to be received by the blowing means, solvent recovery

means, and conduits connected to the solvent recovery means communicating with the upper regions of the spinning cells whereby countercurrent flow of the evaporative medium with respect to the filaments is produced.

5 6. Apparatus for dry spinning artificial filaments comprising a plurality of vertical spinning cells in a row, a spinneret in the upper region of each spinning cell, a manifold back of the spinning cells comprising a main feeding channel and a return channel, conduits connecting the main feeding channel to the spinning cells adjacent their bottoms, take-up means for collecting the filaments in the form of a wound package arranged in front and outside of the spinning cells, means outside the spinning cell for feeding filaments from the cells to the take-up means, means for substantially enclosing the take-up and feeding means, spaced conduits connecting the feeding and take-up means enclosure with the return channel of the manifold, blowing means having its suction side connected with the return channel and its discharge side connected with the main channel of the manifold, heating means arranged between the blowing means and the main channel, means for conducting air from the spinning room to the suction side of the blowing means, means for controlling the proportions of fluid from the return channel and from the spinning room to be received by the blowing means, solvent recovery means, conduits connected to the solvent recovery means communicating with the upper region of the spinning cells whereby countercurrent flow of the evaporative medium with respect to the filaments is produced, and adjustable openings in the take-up means enclosure for controlling the flow of air from the spinning room through the enclosure.
